Inventor

C. C. Henderson & Co.

UNITED STATES PATENT OFFICE.

CHARLES CARROLL HENDERSON, OF JAMESTOWN, NEW YORK.

WASHING-MACHINE.

SPECIFICATION forming part of Letters Patent No. 450,725, dated April 21, 1891.

Application filed January 7, 1891. Serial No. 376,993. (No model.)

To all whom it may concern:

Be it known that I, CHARLES CARROLL HENDERSON, a citizen of the United States, residing at Jamestown, in the county of Chautauqua and State of New York, have invented a new and useful Washing-Machine, of which the following is a specification.

The invention relates to improvements in washing-machines.

10 The object of the present invention is to provide a simple and inexpensive washing-machine adapted to be arranged in a tub and capable of readily yielding to the varying thicknesses of clothes and adapting itself to 15 ordinary apparel and heavy bed-clothing, carpets, and the like without injury to the fabrics.

10 The invention consists in the construction and novel combination and arrangement of 20 parts hereinafter fully described, illustrated in the accompanying drawings, and pointed out in the claims hereto appended.

25 In the drawings, Figure 1 is a perspective view of a washing-machine constructed in accordance with this invention, the parts being shown in operative position. Fig. 2 is a transverse sectional view. Fig. 3 is a horizontal sectional view.

30 Referring to the accompanying drawings, 1 designates a washing-machine designed to be arranged in a tub near the top thereof, to avoid taking up the space necessary for the clothes and water, and composed of a stationary frame 2, carrying a pair of small corrugated rollers 3, and a movable frame 4, having a large corrugated roller 5 and adapted to be 35 swung up when not in use, as illustrated in Fig. 2 of the accompanying drawings, to enable the parts to readily dry after the operation of washing has been completed. The stationary frame 2 is composed of end pieces 40 45 and a horizontal bar 7, secured in recesses at the sides of the end pieces and projecting beyond the same and affording means for securing the washing-machine to the sides of the tub.

The small corrugated rollers 3 are provided at their ends with suitable journals, which are arranged in bearings 8 of the end pieces 50 6, provided with suitable metallic bushings, and arranged intermediate the ends of the corrugated rollers 3 is a fabric band 9, which

encircles the rolls and the horizontal bar 7, which is recessed at 10 to receive the band. Extending from the upper ends of the end 55 pieces 6 of the stationary frame are transverse bars 11, projecting from the ends 6 and provided at their outer ends with bearings 12, in which are journaled pins 13 of end pieces 14 of the movable frame 4, whereby the movable frame is adapted to be swung up for drying, as illustrated in Fig. 2 of the accompanying drawings, and the pins are retained in their bearings by keys 15.

60 The large corrugated roller 5 is mounted 65 upon the shaft 16, journaled in bearings 17 of the movable frame 4 and provided at one end with a crank-handle 18, arranged to extend beyond the sides of a tub to be readily operated. The end pieces 14 of the movable frame are 70 connected by a horizontal bar 19.

75 The large corrugated roller 5 operates in conjunction with the small corrugated rollers 3, and during the operation of washing clothes are passed through the large and small rollers, which are held in their relative positions by spiral springs 20, each having one end connected to the lower end of the movable frame and the other end secured to one end of a rod 21, adapted to engage the end pieces 6 of 80 the stationary frame, which are provided with suitable recesses 22 for the reception of the rod. During the operation of the washer the rolls adjust themselves to the varying thicknesses of clothes or other articles being 85 washed, the springs permitting a lateral movement of the movable frame 4.

90 It will readily be seen that the washer is simple and inexpensive in construction, and is capable of preventing injury to the articles 95 being washed.

What I claim is—

1. In a washing-machine, the combination of the stationary frame carrying the small rollers, the movable frame having its upper 95 end hinged to the stationary frame, the springs connected at one end to the movable frame, and the rod 21, secured to other ends of the springs and adapted to engage the stationary frame, substantially as described. 100

2. In a washing-machine, the combination of the stationary frame comprising the end pieces 6 and the horizontal bar connecting the end pieces and extending beyond the

same, the small rollers journaled between said end pieces, the transverse bars 11, projecting from the end pieces and provided with bearings, the movable frame composed of a horizontal bar and end pieces 14, provided at their upper ends with pins, the shaft journaled in suitable bearings of the movable frame and provided at one end with a crank-handle, the large roller mounted upon the

10 said shaft, and the springs connecting the frame, substantially as described.

In testimony that I claim the foregoing as my own I have hereto affixed my signature in presence of two witnesses.

CHARLES CARROLL HENDERSON.
